UNITED STATES PATENT OFFICE.

BURDETTE H. WHITE, OF SYRACUSE, NEW YORK.

GARMENT-SUPPORTER.

No. 849,763.

Specification of Letters Patent.

Patented April 9, 1907.

Application filed July 28, 1905. Serial No. 271,574.

To all whom it may concern:

Be it known that I, BURDETTE H. WHITE, of Syracuse, in the county of Onondaga and State of New York, have invented a certain 5 new and useful Garment-Supporter, of which the following is a specification:

My invention has for its object the production of a garment-supporter which is particularly simple in construction and highly efficient in use; and to this end it consists in the 10 novel combinations and constructions hereinafter set forth and claimed.

In describing this invention reference is had to the accompanying drawings, in which 15 like characters designate corresponding parts in all the views.

Figure 1 is an elevation of a portion of a suspender embodying my invention. Figs. 2 and 3 are detail views of parts of my suspender. Fig. 4 is a sectional view on line A 20, Fig. 1.

This garment-supporter comprises a member 1, formed with an eye 2 and a pin 3, coöperating with the eye.

In the illustrated embodiment of my garment-supporter the terminal piece or engaging part 4 of a suspender is shown attached to the waistband 5 of a garment, and the 25 ends of said part 4 are bifurcated, each end consisting of two elements or strips 6 7, one 30 preferably lying upon the other, and one of the strips, as 7, being longer than the other strip 6. To the ends of the shorter strips 6 the members 1 are secured, each of said 35 members being formed with a catch, as the socket 8, extending lengthwise thereof and opening into one side of the eye. As shown, each of said members 1 is formed with a loop 9, to which the adjacent end of the strip 6 is 40 secured, and with a lateral loop 10, encircling the overlying strip 7, and usually one of said members is formed with a hook 11 for supporting the underclothes.

The pin 3 is pivoted to the longer strip 7 at 45 the end thereof and is here shown as formed with a loop 12, to which the strip 7 is secured, said pin being movable endwise across the eye and into the socket.

In use the member 1 and the pin 3 are arranged 50 on the same side of the garment, as the outside of the waistband, and the pin is passed through the eye 2 and twice through

the band 5, and the end thereof is extended into the socket 8.

The construction and operation of my garment-supporter will now be readily understood upon reference to the foregoing description and the accompanying drawings, and it will be noted that more or less change may be made in the component parts thereof 55 without departing from the spirit of my invention.

Having thus fully described my invention, what I claim as new, and desire to secure by Letters Patent, is—

1. A garment-supporter comprising a supporting element, a member connected to said element and formed with an eye for receiving a portion of the garment and with a catch at one side of the eye, and a pin movable endwise relatively to the eye member into engagement with the catch, substantially as and for the purpose described.

2. A garment-supporter comprising two supporting elements, a member secured to 75 one of said elements and formed with an eye for receiving a portion of a garment, and a pin secured to the other of said elements and coöperating with the eye member substantially as and for the purpose set forth.

3. A garment-supporter comprising two supporting elements, one lying upon the other, and one being longer than the other, a member formed with an eye secured to the shorter element, said member being also 85 formed with a catch at one side of the eye, and a pin for coöperating with said eye pivoted to the end of the longer element, substantially as and for the purpose described.

4. A garment-supporter comprising a part 90 having a bifurcated end composed of two supporting elements, one lying upon the other, and one being longer than the other, a member formed with an eye secured to the shorter element, and a pin for coöperating 95 with said eye projecting from the end of the longer element, substantially as and for the purpose specified.

5. A garment-supporter comprising a part having a bifurcated end composed of two elements, one lying upon the other and one being longer than the other, a member secured to the shorter element and formed with an eye and with a socket at one side of the eye,

and a pin secured to the longer element and movable endwise across the eye and into the socket, substantially as and for the purpose specified.

5 In testimony whereof I have hereunto signed my name, in the presence of two attesting witnesses, at Syracuse, in the county

of Onondaga, in the State of New York, this 21st day of June, 1905.

BURDETTE H. WHITE.
